PUMP

Hoyt H. Bohannon, Albertville, Ala.

Application September 27, 1944, Serial No. 556,011

5 Claims. (Cl. 103—72)

The invention relates to a water lift apparatus, and more especially to a water pump.

The primary object of the invention is the provision of a pump of this character, wherein through the use of a stripper head having a driven cable passing therethrough, the cable being of a special character, causes water to be lifted from a well, for the discharge of such water out of the pump during the operation of the latter, the pump being of novel construction and is unique in the working thereof.

Another object of the invention is the provision of a pump of this character, wherein the cable of endless arrangement is maintained taut throughout the lifting operation thereof, to assure maximum working conditions through cooperation with the stripper head, for continuous water lifting activity of the pump.

A further object of the invention is the provision of a pump of this character, wherein the water lift cable is supported freely flexible and is susceptible of smooth travel in the working of the pump, there being no oil lubrication required for the successful working of such pump, and all parts thereof are readily accessible for repairs or replacement, the pump being motor driven for the operation thereof, although it may be manually actuated.

A still further object of the invention is the provision of a pump of this character, which is simple in construction, thoroughly reliable and efficient in operation, strong, durable, possessed of few parts, compact, easy of operation, positive in the working thereof, and inexpensive to manufacture and install.

With these and other objects in view, the invention consists in the features of construction, combination and arrangement of parts as will be hereinafter set forth in detail, illustrated in the accompanying drawings, which disclose the preferred embodiment of the invention, and pointed out in the claims hereunto appended.

In the accompanying drawings—

Figure 1 is a vertical sectional view through a water well and pump stand, showing the pump constructed in accordance with the invention installed therewith.

Figure 2 is a front elevation of the pump.

Figure 3 is a vertical sectional view through the stripper head of the pump.

Figure 4 is a sectional view taken on the line 4—4 of Figure 3 looking in the direction of the arrows.

Figure 5 is an enlarged fragmentary vertical

sectional view through the guide thimbles for the water lift cable.

Similar reference characters indicate corresponding parts throughout the several views in the drawings.

Referring to the drawings in detail, A designates generally a portion of a water well, which may be of any well known construction, and B denotes in entirety the pump constructed in accordance with the invention, as will be herein-after more fully described.

The pump B comprises a stripper head in the form of a sectional cylindrical body including the lower and upper sections 10 and 11, respectively, which are inter-threaded at 12 with each other at their ends next to one another. The lower section 10 has fitted thereto at its lowermost end a reducing nipple 13 from which depends at its restricted terminal 14, a standpipe 15, while projecting from the front side of this nipple 13 is a discharge faucet 16, provided with a hand operated plug valve 17 for the turning on and off of such faucet in the usual well known manner. The upper section 11 is formed with an inset seat 18 at its upper portion for stripper diaphragm 19 held thereon by a retaining nut 20, and this diaphragm is made up of several spaced inherently flexible disks for wiper action on an endless flexible water lifting cable 21 which travels through the stripper head and passes through a suitable clearance in such disks. The stripper head forms a water collector chamber 22 therein below the stripper diaphragm 19, so that water stripped from the cable 21 will be trapped in such chamber for delivery to the faucet 16 and discharge therefrom on the opening of its valve 17. The stripper head has its upper section 11 vertically fixed in a stand top 23 of a stand 24 for the pump B, the said stand being mounted directly over the well A, as best seen in Figure 1 of the drawings. The pipe 15 depends a distance within the well A into the water 25 contained therein for the lifting of the latter by the pump when operated.

On the top 23 of the stand 24 is supported an electric power motor 26, its driving shaft 27 carrying a driving pulley 28 having trained thereover the water lifting cable 21, which is in the form of a cotton rope, the weave thereof effecting a regular pattern of small indentations, for water lifting purposes, and such pulley drives the said cable. The upward traveling stretch of this cable 21 lifts the water from the well A, and such stretch passes through the pipe 15, and through the chamber 22 to be acted upon by the diaphragm 19 for the stripping and depositing of

the lifted water into such chamber, this water being let off through the faucet 16 when desired.

At one side of the stripper head and vertically mounted in the top 23 of the stand 24 is a guide nipple 29 for the descending stretch of cable 21 in the travel of the latter when the pump is operating. The lower end of the standpipe 15 has fitted thereto one of a pair of spaced guide thimbles 30 which are united by a cross web 31 for their vertical disposition in receiving the ascending and descending stretches of the cable 21 in the travel thereof.

Centrally of the web 31 is a vertical guide throat or neck 32 for a floating hanger rod 33 carrying a lower guide pulley 34 for the cable 21, the pulley block 35 being fitted with a depending changeable weight 36, which functions to maintain the stretches of the cable 21 taut throughout the working period of the pump B. The cable 21 is provided with a detachable or releasable end coupling 37, so that such cable can be replaced when required.

Overhanging the stripper head and the upper driving pulley of the pump B is a splash box 38, which is held on the top 23 of the stand 24 for shielding purposes.

What is claimed is:

1. A pump of the kind described, comprising a stripper head forming a water collecting chamber, a water lift cable working through the chamber in said head, a wiper diaphragm engaging the cable for stripping water lifted thereby for deposits in the chamber, a discharge faucet on the head and leading from the chamber, power means for operating the cable, means for guiding the

cable in its travel, means for holding the cable taut under travel thereof and a standpipe depending from the head into a body of water within a well and having the cable movable therethrough.

5 2. A pump of the kind described, comprising a stripper head forming a water collecting chamber, a water lift cable working through the chamber in said head, a wiper diaphragm engaging the cable for stripping water lifted thereby for deposits in the chamber, a discharge faucet on the head and leading from the chamber, power means for operating the cable, means for guiding the cable in its travel, means for holding the cable taut under travel thereof, a standpipe depending from the head into a body of water within a well and having the cable movable therethrough and a support for the head.

10 3. The invention as described in claim 2 wherein in the means for guiding the cable in its travel comprises a pair of spaced guide thimbles united for vertical disposition with said cable by a cross web formed at their medial points.

15 4. The invention as described in claim 2 wherein in the means for holding the cable taut is supported by a floating hanger rod, mounted in a vertical guide throat formed in the medial portion of a cross web uniting spaced guide thimbles for said cable.

20 5. The invention as described in claim 2 wherein in the means for holding the cable taut comprises a pulley block having a depending changeable weight fitted thereon.

HOYT H. BOHANNON.
